R. L. CARTER

BLOWER FOR ROUTING MACHINES

Filed Feb. 7, 1925

UNITED STATES PATENT OFFICE.

RAY L. CARTER, OF SYRACUSE, NEW YORK.

BLOWER FOR ROUTING MACHINES.

Application filed February 7, 1925. Serial No. 7,728.

To all whom it may concern:

Be it known that I, RAY L. CARTER, a citizen of the United States, residing at Syracuse, in the county of Onondaga and State 5 of New York, have invented certain new and useful Improvements in Blowers for Routing Machines, of which the following is a specification.

This invention relates to means for automatically removing the chips and dust, resulting from the operation of routing and like tools from the work, and has for its object to provide a novel head for the casing that encloses the air-cooled electric motor which drives the tools, by means of which the air exhausted from the motor casing may be discharged into the mortises or sockets formed by the tools. And a further object is to provide a motor casing head, that is 10 formed with a cavity in which a fan is operatively disposed, the said fan being mounted upon and driven by the armature shaft, and being arranged to draw air through the motor for cooling the same, and then to force 15 the air downwardly through tapering nozzle-like openings, by which the air may be directed in several streams that converge at or near the point where the routing or shaping tool is performing its cutting work, thereby 20 continuously blowing the dust and chips from the mortises and preventing the overheating of the tool, and enabling the operator at all times to obtain a clear view of and to control the tool and its execution. 25

The cavity in which the fan rotates is preferably arranged for facilitating the free exhaust of the air through the funnel-shaped openings of the head without retarding the fan. 30

I attain these objects by the means set forth in the detailed description which follows and as illustrated by the accompanying drawing in which—

Figure 1 is a front side elevation of a routing machine with parts broken away for showing the construction and arrangement of the dust and chip remover; also showing the tool in the act of routing or mortising a piece of work. Fig. 2 is a top plan view 45 of the head of the motor casing, the point of separation of the head from the casing being indicated by line 2—2 of Fig. 1. And Fig. 3 is a bottom face view of the motor casing head.

In the drawing, 2 represents an electric motor, including the armature shaft 3. The

motor 2 is preferably enclosed in a cylindrical casing 4, which is normally open at its top and bottom ends, the top end preferably being closed by a cap 4', which supports 60 the corresponding end of the shaft 3, and also the terminals, as 5—5', of the electric circuit, by which the motor is controlled. The bottom end of the casing 4 is preferably closed by a removable conical head 6, which 65 serves as a bearing for the lower end of the shaft 3, the said end extending below the head, and being threaded for the attachment of an ordinary chuck, as 7, which supports the routing or shaping tool 8. The armature shaft 3 is provided with a ball-bearing 70 as 9, which is supported by the head, as shown in Fig. 1. Above the said bearing the head is formed with a relatively large upwardly facing cavity 6', in which is disposed a fan 10, the latter being rigid on the shaft 3, and between the fan and the armature is preferably disposed a disc 10', which 75 rests upon an annular ledge 6'a that surrounds the cavity 6'. The disc 10' has a central opening 10'a, through which the air employed for cooling the motor is drawn downwardly by said fan. Below the cavity 6' and communicating therewith, the head is 80 formed with similar funnel-shaped passages or openings 12—12', which preferably taper downwardly at such angles, as to direct the air exhausted from the motor in similar converging streams towards the cutting end of the tool 8, as shown by arrows in Fig. 1. 90 The tips of the blades 10'b of the fan preferably travel in a circle, as indicated by the broken line 10'e in Fig. 2, and in order to render the exhaust of the air effective for blowing the dust and chips from the mortise 95 or socket, as 13 of the work 13', and for cooling the tool, the cavity 6', beyond the normal path 10'c of the fan, is formed with similar oppositely facing spiral or eccentric portions, as 6"—6", which expand as they 100 approach the funnel-shaped outlets 12—12', and both of said spirals preferably terminate at abrupt radial shoulders 12'a, which form portions of the flaring mouths of the said outlets. By this construction and arrangement the air that is collected and driven forwardly by the rapidly rotating fan is readily forced downwardly into the said outlets, and by reason of the contraction of the lower ends of said outlets, the air becomes more or 105 less compressed and is therefore discharged from the head with sufficient force to effec-

2
tually clear the sockets 13 and at the same time tends to keep the high-speed tool 8 cool. By the provision of the spiral recesses 6^b—6^c, the fan 10 may be operated at extremely high speed, without danger of the fan being retarded by the cushioning of the air in the cavity 6.

The router, comprising the motor 2 and the tool 8, is supported in a cylindrical holder 14, which is provided with oppositely projecting perforated arms 14', which receive and are slidable vertically on similar tubular guides 15, the said guides having their lower ends anchored in sockets 16' of a base 16, which is provided with a plane bottom that rests on a surface of the work 13. In the guides 15 are disposed coil compression springs 15', which tend to lift and hold the motor and tool away from the work. These springs are compressible by means of pins 15^a, which pass through the guides and engage the top ends of the springs. The motor and tool are moved downwardly towards the work, by means of pawl-and-ratchet mechanisms, which comprise teeth 15^b formed in the outer faces of the guides, and pawls 17, which are pivoted to the lower ends of links 17', the upper ends of said links being pivoted to the arms 14'. The pawls are provided with loops 17^b, through which the operator inserts a finger of each hand, for depressing the loops and lowering the motor and tool towards the work 13. The operator usually places his thumbs beneath lugs 18, which are integral to the sockets 16'.

By this construction and arrangement the tool 8 may be moved downwardly step by step, for routing or mortising to different depths, as shown in Fig. 1. To release the tool 8, the operator presses inwardly on the upwardly projecting ends 17^a of the links. This effects the outward swinging of the pawls free of the teeth, and allows the tension of the springs 15' to lift the motor and tool away from the work. The base 16 is cut-away centrally, as at 16^a, or affording clearance for the tool 8, and for enabling the operator to readily observe and guide the tool. The value of my improved blower will be appreciated when it is understood that in all accurate and precise work, it is necessary to keep the surface of the work 13, over which the plane bottom of the base 16 slides, free and clear of even the smallest solid particles, which might cause the slightest variation in the level or depth of the cuttings.

The cooling of the tool 8 is also a valuable and material feature of my invention. My routing machines are operated by specially built electric motors, which for routing and shaping work develop a speed, when the tools are running light, of from 14,000 to 18,000 R. P. M. The routing or shaping

work is usually effected at speeds which vary between 8,000 and 12,000 revolutions per minute, owing to whether the work comprises, for example, soft pine, or hard dry birch. At either of said working speeds the tool 8 tends to heat up, and I have found that by directing strong streams of air towards the cutting point, as herein shown and described, the tool may be maintained at substantially normal temperature during long periods of work.

Having thus described my invention, what I claim, is—

1. The combination with a driven tool-carrying shaft, of a hollow conical head surrounding the shaft, said head being formed interiorly with openings arranged to direct streams of air that converge near the free end of the tool, a fan mounted upon and driven by said shaft, said fan being located within the hollow head adapted to force air continuously through the said openings and into the sockets wrought by said tool, for blowing dust and chips from the said sockets, the interior of the head being arranged with oppositely facing spiral recesses which communicate with the openings.

2. The combination with a driven tool-carrying shaft and means to drive said shaft, of a cylindrical casing surrounding the driving means and having an end thereof formed with a concentric cavity that faces the driving means and with funnel-shaped openings below and communicating with the cavity, corresponding portions of the outer margins of said cavity being enlarged spirally and said spiral portions terminating in abrupt shoulders, the said openings tapering towards the line of the axis of said tool, a fan driven by said shaft, said fan being disposed in said cavity adapted to force continuous streams of air through said openings for cooling the tool and for blowing chips and dust from mortises and cavities wrought by the tool.

3. The combination with air-cooled driving means and a tool-carrying shaft connected thereto and a tool driven by said shaft, of a cylindrical casing surrounding the driving means, a hollow head for closing the bottom end of the casing, said head being formed with an upwardly facing cavity and with a plurality of downwardly tapering openings that communicate with said cavity, the said openings being arranged to direct streams of air adapted to converge at or near the free end of the tool, a fan mounted upon and driven by said shaft, said fan being disposed in said cavity adapted to draw the air by which the driving means is cooled downwardly through the casing and to continuously force the air through said tapering openings for blowing chips and dust that result from the cutting by said tool, away from the work, and means

for facilitating the free exhaust of the air from said cavity and for preventing the retarding of the fan.

4. A blower for work-performing tools including tool-driving means, a hollow conical head through which the tool projects having a fan chamber, and a fan carried by said means arranged in the chamber, said head having independent downwardly converging openings disposed below the fan and each separately communicating with the chamber so as to direct independent streams of air on opposite sides of the tool.

5. A blower for work-performing tools including tool-driving means, a hollow conical head through which the tool projects, and a fan carried by said means, said head having independent downwardly converging openings disposed below the fan so as to direct independent streams of air on opposite sides of the tool and having opposed spiral walls leading into the respective cavities, the fan operating between the walls.

In testimony whereof I affix my signature.

RAY L. CARTER.
